United States Patent

Des. 236,163
Patented July 29, 1975

236,163

FLUID DELIVERY APPARATUS

Joseph J. Manno, La Jolla, Calif., assignor to
IVAC Corporation, San Diego, Calif.

Filed Sept. 16, 1974, Ser. No. 506,615

Term of patent 14 years

Int. Cl. D24—02

U.S. Cl. D83—1 F

Fig. 1

Fig. 3

Fig. 2

Fig. 5

Fig. 4

FIG. 1 is a front perspective view of a fluid delivery apparatus embodying my new design;

FIG. 2 is a left side elevational view of the apparatus shown in FIG. 1;

FIG. 3 is a rear elevational view of the apparatus shown in FIG. 1;

FIG. 4 is a top plan view of the apparatus shown in FIG. 1; and

FIG. 5 is a bottom plan view of the apparatus shown in FIG. 1.

I claim:

The ornamental design for a fluid delivery apparatus, as shown.
